(57) **CLAIM**

The ornamental design for a recessed back of a golf club head, as shown and described.

DESCRIPTION

FIG. 1 is a perspective view of the recessed back portion of a golf club head;

FIG. 2 is a elevational view;

FIG. 3 is a top plan view;

FIG. 4 is a planar section taken along lines 4—4 in FIG. 2; and,

FIG. 5 is a planar section taken along lines 5—5 in FIG. 2.

The broken line showing of a golf club head is for illustrative purposes only and forms no part of the claimed design.
